CLOCK

Gordon Florian, Fairfield, Conn., assignor to Sunbeam
Corporation, Chicago, Ill., a corporation of Illinois

Filed June 29, 1964, Ser. No. 80,614

Term of patent 14 years

(Cl. D42—7)

FIG. 1 is a front elevational view of a clock embodying my new design;

FIG. 2 is a top plan view thereof;

FIG. 3 is a side elevational view thereof;

FIG. 4 is an enlarged fragmentary sectional view taken along line 4—4 of FIG. 1;

FIG. 5 is an enlarged fragmentary sectional view taken along line 5—5 of FIG. 1; and

FIG. 6 is an enlarged fragmentary sectional view taken along line 6—6 of FIG. 1.

I claim:

The ornamental design of a clock, as shown.
